UNITED STATES PATENT OFFICE.

ROBERT M. VARDAMAN AND ALBERT T. VARDAMAN, OF IRONATON, ALABAMA.

SOD-LINER.

1,072,798.

Specification of Letters Patent.

Patented Sept. 9, 1913.

Application filed March 8, 1912. Serial No. 682,512.

To all whom it may concern:

Be it known that we, ROBERT M. VARDAMAN and ALBERT T. VARDAMAN, citizens of the United States, residing at Ironaton, in the county of Talladega, State of Alabama, have invented certain new and useful Improvements in Sod-Liners; and we do hereby declare the following to be a full, clear, and exact description of the invention, such 10 as will enable others skilled in the art to which it appertains to make and use the same.

This invention relates to new and useful improvements in sod liners for trackmen or 15 the like.

An object of this invention is the provision of a sod liner for lever cars or the like and which is so constructed that when attached to a car it will mark a line parallel 20 to the track providing a means for gaging the distance for digging ditches, laying sod or the like.

A further object of this invention is the provision of a sod liner which will be comparatively simple and inexpensive to manufacture, reliable and efficient in use and readily operated.

A further object of this invention is the provision of a sod liner which can be very 30 quickly applied to or removed from a lever car and which when applied can be adjusted to any desired position relative to the said car.

With the above and other objects in view, 35 this invention resides in the novel features of construction, formations, combinations and arrangements of parts to be hereinafter more fully described, claimed and illustrated in the accompanying drawings, in 40 which:—

Figure 1 is a top plan view of our invention. Fig. 2 is a side elevation thereof. Fig. 3 is a transverse sectional view thereof. Fig. 4 is a longitudinal sectional view 45 thereof. Fig. 5 is a detailed sectional view of a portion of our invention.

Referring to the accompanying drawings by similar characters of reference throughout the several views, the numeral 10 designates generally a car which is supported by the customary sills 11 which consist of the longitudinally extending upper and lower members 12 and 13, the said members 12 and 13 being held in spaced relation to each 50 other by spacing blocks 14. The beams 12 and 13 are provided adjacent their termi-

nals with registering bearings 15 and 16 shown in the accompanying drawings as being arranged upon the opposite sides of the beam, this being shown merely to indicate that the same may be placed in either 60 position.

A pair of links 17 are pivotally connected between the bearings 15 and 16 by means of a pivot pin 18, while the outer ends of 65 these links extend within recesses 19 formed in the opposite sides of a supporting block 20, in which recesses 19 the ends of the links 17 are pivotally connected by bolts or other similar fastening devices 21.

A connecting plate 22 is attached to the intermediate portions of the beams 12 and 13 and is formed with a socketed extension 23 for the reception of one end of a bar 24. The bar 24 extends through a longitudinal 75 slot or opening 25 formed in the block 20. The bar 24 is formed with a plurality of perforations 26 to provide a means whereby the extension bar 27 which also passes through the opening 25 may be adjustably 80 connected thereto as indicated by the numeral 28. The free end of the extension bar 27 is formed with a vertical opening 29 in which is removably supported and held against rotation a marking standard 30 85 which carries journaled upon its lower end a marking disk 31 adapted for engagement with the ground whereby a line will be marked parallel to the track upon the passage of the car which supports the improved 90 marker.

From the foregoing disclosures taken in connection with the accompanying drawings, it will be manifest that a sod liner such as described is provided for which will 95 fulfil all of the necessary requirements of such a device. It should be understood in this connection that various minor changes in the details of construction may be resorted to within the scope of the appended claim 100 100 without departing from or sacrificing any of the advantages of the invention.

Having thus fully described this invention what we claim as new and desire to protect by Letters Patent, is:

The combination with a car body, of a 105 block having a passage therethrough disposed at right angles to the car body, links having one end connected to the car body and their other ends connected to the block 110 and supporting the latter at one side of the car body, an arm comprising inner and outer

sections, the inner end of the inner section being supported by the car body and the outer and inner ends of said sections being disposed in overlapped relation within the passage of said block and provided with perforations adapted to be brought into successive registration by relative longitudinal movement of said sections, a bolt carried by the block and engaged through registered openings of the sections, and a

marker carried at the outer end of the outer section.

In testimony whereof, we affix our signatures, in presence of two witnesses.

ROBERT M. VARDAMAN.
ALBERT T. VARDAMAN.

Witnesses:

J. L. McLANE,
K. H. CAMP.
